(57) CLAIM

The ornamental design for a shoe as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof;

FIG. 7 is an opposite side front perspective view thereof; and,

FIG. 8 is a front view thereof.

The broken line showings of the rectangular strip on the tongue of the shoe and the diamond-shaped region on the rear of the shoe form no part of the claimed design. The broken line round rectangular regions within the shaded area represent eyelets that form no part of the claimed design. The contrast in shading represents a contrast in appearance only, and does not represent any particular color, material, texture, or finish. The broken line immediately adjacent to the shaded area defines the bounds of the design and forms no part thereof. The broken lines depicting the remainder of the shoe form no part of the claimed design.
